J. J. SOMERS

FASTENER FOR REVERSIBLE GARMENTS

Filed Aug. 31, 1922

UNITED STATES PATENT OFFICE.

JOHN J. SOMERS, OF BRIDGEPORT, CONNECTICUT.

FASTENER FOR REVERSIBLE GARMENTS.

Application filed August 31, 1922. Serial No. 585,516.

To all whom it may concern:

Be it known that I, JOHN J. SOMERS, a citizen of the United States, and a resident of Bridgeport, in the county of Fairfield 5 and State of Connecticut, have invented new and useful Improvements in Fasteners for Reversible Garments, of which the following is a full, clear, and exact description.

This invention relates to fasteners for reversible garments and was primarily designed for use with corsets and other similar garments.

Generally in the construction of corsets and other similar garments, they are not made so that they may be reversed. Consequently, when the corset or other similar garment, which has been finished on one side, becomes worn on that finished side it has to be discarded. If means were provided for converting the corset and similar garments into reversible garments they might be finished on both sides so that when one finished side became worn or soiled so as not to present a good appearance it might be reversed, displaying the other finished side which had not been worn. Thus the provision of fastening devices in conjunction with garments, converting them into reversible garments, would greatly reduce the expenditure required in supplying the wearers of such garments.

The general object of this invention is the provision of fastening devices for use with corsets and similar garments for converting them into reversible garments.

A further object of the invention is the provision of fastening devices for mounting on corsets and similar garments so that the corsets and similar garments may be reversed to prolong the life of the garments.

These objects are accomplished by mounting a plate having loop members on one edge of the garment, attaching to the other edge of the garment a plate provided with a plurality of sliding studs that may be projected to either side of the plate for engaging with the loop members on either side of the garment, and providing in conjunction with the garment flaps which extend on both sides of the plate carrying stud, these flaps having plates mounted therein for protecting the studs to either side of the stud carrying plate.

These and other objects of the invention will be more clearly understood from the

following detailed description and accompanying drawings.

Figure 1 is a perspective view of a corset provided with the fastening device, displaying one of the finished sides of the 60 corset;

Figure 2 is a perspective view of the corset, showing it reversed, displaying the other finished side;

Figure 3 is a front plan view of the meeting edges of the corset with a portion cut away displaying part of the fastening device;

Figure 4 is a section along the line 4—4, Figure 3;

Figure 5 is a section along the line 5—5, Figure 3;

Figure 6 is a side elevation of the stud carrying plate, showing the studs in different positions.

Referring to the above-mentioned drawings, the fastening means includes a plate 10 having a plurality of eye members 11 attached thereto. This plate 10 is attached to one edge 13 of the corset 12 by projecting 80 it between the different layers of the fabric of the corset and fixing it in position in any usual manner such as sewing together the edges of the different layers of fabric forming the corset. A plate 14 having a plurality of studs 15 slidably mounted therein is enclosed in a piece of fabric 16 with the studs 15 extending through the fabric. The edges of the fabric 16 are then projected between the layers of fabric 17 and 18, used 90 in constructing the corset, and attached in position by a line of stitches 19. Flaps 22 and 23 are formed from the two outer layers of the fabric used in making the corset by folding them back on themselves, enclosing 95 the plates 20 and 21. The folds are retained in the fabric by the line of stitches 19 which also holds the fabric 16 in position. These flaps, as shown in Figure 4, extend outward, one on each side of the stud carrying 100 plate 14.

In the preferable construction of the corset as shown in Figures 1, 2 and 3, the fastening device described above would not extend the full length of the corset but would only be provided in conjunction with the upper portion of the corset. The edges of the lower portion would be joined together by means of a lacing cord 24.

In using a fastening device of this type,

- all the wearer has to do in order to fasten the corset or other similar garment is to press one of the flaps 22 or 23 into engagement with the studs 15, projecting them to the side of the plate on which it is desired to attach the loop members or eyes 11. The loop members are then fitted over the ends of the studs in the ordinary manner. The flaps 22 and 23 protect the wearer and the garments which are located outside of the corset from the heads of the studs. In providing a reversible garment of this type it is also necessary to provide reversible suspenders 25.
- 15 I would state in conclusion that while the illustrated example constitutes a practical embodiment of my invention I do not limit myself strictly to the exact details herein illustrated since manifestly the same can be considerably varied without departing from the spirit of the invention as defined in the appended claims.

Claims.—

1. A fastener for reversible garments, comprising loop members carried by one edge of the reversible garment, studs slidably mounted in the other edge of the reversible garment, and means attached to the reversible garment for forcing the studs to either side of the reversible garment to engage the loop members.
2. A fastener for corsets and similar garments, comprising loop members carried by one edge of the corset, means adjustably mounted in the other edge of the corset for engaging the loop members, and means carried by the corset for setting the adjustable engaging means to engage the loop members on either side of the corset.
3. A clasp for reversible garments, comprising steels attached to each edge of the reversible garment, eye members mounted on one steel, studs slidably mounted in the other steel, and means carried by the reversible garment for forcing the studs to either side of the steel for engaging the eye members.
4. A device of the class described for fastening reversible garments, comprising eye

members, means for mounting the eye members on one edge of the reversible garment, studs for engaging the eye members, means for mounting the studs on the other edge of the reversible garment so that they may be projected to either side of it, and means carried by the reversible garment for forcing the studs to either side of it.

5. In combination with a reversible garment, a device of the class described for fastening the garment, comprising eye members mounted on one edge of the garment, studs mounted on the other edge of the garment so that they may be forced to either side of the same, and flaps carried by the garment for projecting the studs to either side of the garment to engage the eye members.

6. In combination with corsets or similar garments, a device of the class described for fastening them, comprising a plate mounted in one edge of the garment, loop members carried by said plate, a second plate mounted in the other edge of the garment, studs slidably mounted in the second plate, flaps carried by the garment and projecting outward, one lying on each side of the second plate carrying the studs, and plates mounted in each of said flaps for projecting the studs to either side of the stud carrying plate.

7. In a corset fastening device of the class described including a plurality of loop members carried by one edge of the corset, means mounted on the other edge of the corset to engage the loop members, comprising a plate having studs slidably mounted therein so that they may be projected to either side of the plate to engage the loop members on either side of the plate.

8. A fastener for reversible garments, comprising loop members carried by one edge of the reversible garment, and studs slidably mounted in the other edge of the reversible garment so that they may be projected to either side of the reversible garment to coact with the loop members to connect the edges of the garment together.

JOHN J. SOMERS.
